United States Patent

Des. 234,514
Patented Mar. 18, 1975

234,514

UTILITY SPRAYER

William J. Kimmers, Sioux City, Iowa, and Clarence E. Stewart, South Sioux City, Nebr., assignors to The Broyhill Co., Dakota City, Nebr.

Filed July 25, 1973, Ser. No. 382,443

Term of patent 14 years

Int. Cl. D23—01

U.S. Cl. D23—18

FIG. 2

FIG. 1

FIG. 3

FIG. 4FIG. 5FIG. 6FIG. 1 is a perspective view of a utility sprayer showing our new design. The broken line representation of a motor and a spray nozzle in FIG. 1 is for purposes of illustration only.

FIG. 2 is a front view thereof,
FIG. 3 is a side view thereof,
FIG. 4 is a top view thereof,
FIG. 5 is a bottom view thereof, and
FIG. 6 is a rear view thereof.

We claim:

The ornamental design for a utility sprayer, as shown and described.
